US00D514778S

(12) **United States Design Patent** (10) Patent No.: **US D514,778 S**
 Berg et al. (45) Date of Patent: **** Feb. 14, 2006**

(54) **SHOE**

(76) Inventors: **David Berg**, 218 Dumaire, White Lake, MI (US) 48383; **Thomas E. McGann, III**, 2349 Ethal, White Lake, MI (US) 48390

(**) Term: **14 Years**

(21) Appl. No.: **29/215,322**

(22) Filed: **Oct. 18, 2004**

Related U.S. Application Data

(63) Continuation-in-part of application No. 10/911,069, filed on Aug. 4, 2004, which is a continuation-in-part of application No. 10/011,117, filed on Nov. 13, 2001, now Pat. No. 6,792,696.

(74) *Attorney, Agent, or Firm*—Gifford, Krass, Groh, Sprinkle, Anderson & Citkowski, P.C.

(57) **CLAIM**

We claim the ornamental design for a shoe, as shown and described.

DESCRIPTION

FIG. 1 is a perspective view of a shoe according to the present invention;

FIG. 2 is a front elevational view of the shoe of FIG. 1;

FIG. 3 is a rear elevational view of the shoe of FIG. 1;

FIG. 4 is a top plan view of the shoe of FIG. 1;

FIG. 5 is a bottom plan view of the shoe of FIG. 1;

FIG. 6 is a side elevational view of the shoe of FIG. 1; and,

FIG. 7 is an opposite side elevational view of the shoe of FIG. 1.
